LOW GRID CURRENT GLOW TUBE

Dewey D. Knowles, Wilkinsburg, Pa., assignor to Westinghouse Electric & Manufacturing Company, East Pittsburgh, Pa., a corporation of Pennsylvania

Application December 9, 1936, Serial No. 114,967

2 Claims. (Cl. 250—27)

My invention relates to discharge devices and especially to grid controlled glow tubes.

An object of my invention is to provide a tube having effective control by a grid with very small grid currents.

Other objects and advantages of my invention will be apparent from the following description taken in conjunction with the drawing, in which:

Figure 1 is a sectional view of a tube embodying 10 my invention;

Fig. 2 is a top plan view of the grid in Fig. 1;

Fig. 3 is a sectional view of a modification of Fig. 1; and,

Fig. 4 is a sectional view of the cathode enclosure of Fig. 3.

In the construction of grid controlled glow and arc discharge tubes, one of the principal problems is to so design the grid that the current flowing to it at the critical starting point is very small. The ideal tube would, of course, be one in which this current is zero as in high vacuum or hard tubes. The grid current in a gas filled tube, assuming zero grid emission is that due to ions and electrons that are collected by the grid from the gaseous medium around it which is slightly ionized by the pre-ignition or threshold discharge just preceding the arc or glow discharge. In gas filled tubes, especially those for heavy current and voltage industrial uses, the size of the electrodes have been increased in order to provide higher ratings. With the increased size of the grid, the grid current necessary at the critical starting point has also become considerably greater. The increase in size of the grid is also the result of trying to prevent the discharge occurring around the grid by completely isolating the anode from the cathode by the grid and thus compelling the discharge to take place through the meshes or other opening of the grid.

In the prior art this isolation by the grid has been taken care of in two ways. In one instance the grid extends completely across the tube between the glass walls, so that there is no other path from the cathode to the anode than through the grid openings. This structure is objectionable because the grid touches the glass walls and cannot be outgassed, because the heat treatment would damage the glass walls.

Another modification has been to surround both the cathode and the anode with a cylindrical grid having a perforated or mesh partition between the anode and cathode. This structure, since it encloses both the cathode and the anode, is very large and because of its large size requires excessive grid current.

According to my invention, I provide an enclosure about the active portion of the cathode with a limited opening facing the other main electrode. This enclosure is preferably at a negative charge or potential relative to the cathode, so that the electrons must pass through the opening to the anode. The control grid may now be made of very small size adjacent to or covering the opening. Because of its small size, the grid current will be kept very small. Of course, I also contemplate that the anode may also be enclosed, if desired, instead of or in addition to this enclosure about the cathode. My preference, however, is for such an enclosure or guard electrode about the cathode.

In Fig. 1 is disclosed a preferred embodiment of my invention comprising the container 10 having a gaseous medium 11 which may be of any of the noble gases, such as neon or argon, or it may be of mercury vapor. The cathode 12 is 20 preferably of the directly heated type although the indirectly heated type may be used. This cathode is preferably coated with the electron emitting coating, preferably including barium and strontium oxides. This cathode also preferably 25 has the lead wires 13 supporting it from the re-entrant press 14. The anode 15 is preferably supported from a press 16 located at the opposite end of the tube from the cathode press 14.

Around the cathode 12, I provide an enclosure 17 that preferably encloses the effective area of the cathode 12, except for an opening 18 in this enclosure facing the other main electrode, namely, the anode 15. This enclosure 17 can be supported very conveniently from the press 14 by the band 19 and this enclosure may have a separate lead 20 passing through any convenient portion of the tube wall including the press 14. Adjacent the opening 18, I preferably provide a grid structure 21. As disclosed in Fig. 2 this grid structure 40 preferably comprises an annular ring 22 having bars 23 extending thereacross. These bars may be kept in place by tabs 24 attached to the ring 22 or by any other convenient supporting means. A preferred material for these bars is graphite 45 or carbonized nickel because this material is non-emissive even when hot. In place of these bars a material having a mesh form or other perforations may be utilized. In any case the size of the grid proper is very small because it is accommodated to the limited opening 18 which would probably be about $1/2$ " in diameter.

This grid may be conveniently supported in position by wires 25 which may extend to one of the presses such as 16. A grid lead 26 may pass 55

through the tube at any convenient position. In operating the device I preferably put a charge or potential on the cathode enclosure 17 that is more negative than the cathode 12 in order that the electrons will necessarily pass through the opening 18 to reach a more positive electrode such as the anode 15.

In Fig. 3, I disclose a further modification in which my invention is applied to an anode concentrically or radially placed in respect to the cathode. The container 10 has its gaseous medium 11 as in Fig. 1. I disclose, however, in this embodiment only a single reentrant press 30 for the support of the electrodes although, of course, other presses may be used. The cathode 31 is illustrated as the directly heated type and is placed in an axial position. The enclosure for the cathode in this case is approximately that of a closed end cylinder cut in half and separated for the emission of electrons. The lower half cylinder 32 may be supported by a lead 33 from the press 30. The upper half cylinder 34 may be supported from the lower portion by bars 35 welded or otherwise secured to the two parts. The upper portion 34 also preferably has an extension 36 supporting an insulating plate 37 such as glass. The space 38 between the two portions of the enclosures 32 and 34 is surrounded by a mesh or perforated cylinder 39 to act as a control grid. This perforated cylinder is supported from the press 30 by the lead 40 and the standard 41. It is preferred to have the grid fixed in position by extending certain standards 42 from the upper portion of this grid structure to be secured in the insulating plate 37 by fusion thereto at 43. An anode 44 of any desired shape and configuration surrounds this assembly of electrodes and preferably has a supporting lead 45 from a band 46 surrounding the press 30. An anode lead 47

may extend through the tube wall at any desired location including that of the press 30.

It will be noted that in this case also, I have utilized a grid area small in size and also material for controlling the electron emission from the opening 38 of the cathode enclosure. In this case also I prefer to put a charge on the cathode enclosure that is more negative in respect to the cathode.

It is obvious that many changes may be made in the size, shape and arrangement of the various elements and also in their combinations. Accordingly, I desire only such limitations to be imposed upon the following claims as are necessitated by the prior art.

15 I claim as my invention:

1. In combination, a discharge device comprising an envelope containing a gaseous atmosphere, an electron-producing electrode, an enclosure therefor having an opening, an electron collecting electrode, an electrode controlling the passage of electrons from said opening to said electron collecting electrode, and means for impressing upon said enclosure a negative continuous electrical potential relative to said electron-producing electrode, the other said electrodes being outside the compass of the walls of said enclosure.

2. A discharge device comprising a container having a gaseous atmosphere therein, an anode, a cathode, a grid interposed between said cathode and anode and an enclosure for said cathode having an opening adjacent said grid, and means for imparting to said enclosure a definite continuous electrical potential of substantial magnitude relative to said cathode, said grid and anode being outside the compass of the walls of said enclosure.

35 DEWEY D. KNOWLES.
